UNITED STATES PATENT OFFICE.

FRANCIS W. BRADY, OF ENGLEWOOD, NEW JERSEY, ASSIGNOR TO ELECTRIC BOAT COMPANY, OF NEW YORK, N. Y., A CORPORATION OF NEW JERSEY.

RECIPROCATING-PISTON ENGINE.

SPECIFICATION forming part of Letters Patent No. 737,201, dated August 25, 1903.

Application filed November 6, 1902. Serial No. 130,225. (No model.)

To all whom it may concern:

Be it known that I, FRANCIS W. BRADY, a citizen of the United States, residing at Englewood, in the county of Bergen and State of New Jersey, have invented certain Improvements in Reciprocating-Piston Engines, of which the following is a specification.

This invention relates to the class of reciprocating-piston engines wherein a more or less irregular reciprocating movement of the piston is required, as in the case of engines employed for operating steering mechanisms, and the invention resides mainly in the gear whereby the piston-rod in its reciprocating movements actuates and controls the movements of the engine-valve.

The object of this invention, so far as it relates to the valve-gear, is to provide means for shifting the valve from the cut-off or central position in either direction independently of the piston, for setting the latter in motion, and for controlling the extent of movement required of the piston to return the valve to the cut-off position again, whereby the piston may be arrested at any point in the cylinder that may be required.

Another object is to provide means whereby the piston may be moved in the cylinder by hand to any point required, and another is to provide means for operating the air-controlling valve in unison with the engine-valve.

The gear for operating the valve comprises a rocker or rocking lever having one arm coupled through suitable devices with the piston-rod and two slotted arms at opposite sides of its fulcrum and another rocker or rocking device the fulcrum of which slides or is movable, an arm on the shaft of this device being coupled to the stem of the engine-valve.

This rocking device has studs adapted to be put into engagement with the slots in the arms of the other rocking lever or device. By shifting the fulcrum of the rocking device which is coupled to the valve the latter may be shifted without disturbing the piston or rod of the engine, and this shifting also moves the engaging stud more or less deeply into the slot in the arm of the other rocking device, thereby varying the leverage and with it the extent of movement of the piston relatively

to the movement required to return the valve to the cut-off point.

My invention is adapted to steering mechanisms for vessels, to the regulation of the stroke of a hydraulic or pneumatic press or punch, to fluid-operated railroad-signals, for setting the signal in different positions, for regulating pressure-reducing valves, and for many other uses that I need not enumerate here.

In the accompanying drawings, Figure 1 is a sectional side elevation, the engine being shown in vertical axial section. Fig. 2 is a sectional plan, the valve-chests being in horizontal section. Fig. 3 is a sectional plan view of the intermediate valve-operating mechanism; and Fig. 4 is a side elevation of this mechanism, showing the side opposite to that seen in Fig. 1. Figs. 5, 6, and 7 are respectively transverse sections in substantially the planes indicated by lines x^5 , x^6 , and x^7 in Fig. 1. Fig. 8 is a view showing the piston at the end of its predetermined movement.

In the particular embodiment of the invention herein shown, 1 is a suitable bed-plate, 2 is the engine cylinder mounted thereon.

3 is the piston.

4 is the piston-rod.

5 is the valve-chest, 6 is the double piston-valve therein, and 7 is the stem thereof.

8 is the exhaust port and passage.

9 represents the port-passages leading from the ends of the chest to the cylinder, and 10 is the inlet for a liquid, as oil, forced or under pressure to the ends of the valve-chest.

11 is a by-pass connecting the ends of the cylinder, and 12 is a stop-valve controlling same. In the exhaust 9 is also a stop-valve 13.

In a chest 14 at the side of the main valve-chest 5 is a slide-valve 15. This valve controls the supply of compressed air to the oil-pump. (Not shown.) The air from a compressed-air chamber or reservoir enters the chest 14 at an inlet 16 and exhausts therefrom to the pump at an exhaust-outlet 17.

The stems 7 and 18 of the respective valves 6 and 15 are coupled to a cross-head 20, and this cross-head or tie-piece is coupled by a link 21 with an arm 22 on a rock-shaft 23, which has bearings in slide-block 19, mounted

in horizontal guides in a suitable upright frame 24 on the bed-plate.

On the rock-shaft 23 is pinned or keyed a floating rocker or rocking lever 25, which is disposed at right angles to the arm 22 and carries at its respective ends roller-studs 26. (Seen clearly in Fig. 3.) These studs engage, respectively, slots 27 in the shorter arms of a T-shaped rocker or rocking lever 28, Fig. 4, the longer pendent arm of which is pivotally connected at 29 with a block 30, which plays in a guideway in a pendent bracket 31, secured to the piston-rod, Fig. 6. The rocker 28 has a bearing on and turns about a stud 32, secured in a support 33 on the bed-plate, and said stud is alined with the rock-shaft 23 when the parts are in the position seen in Fig. 1.

It may be explained here that the liquid, as oil, used in the engine to move the piston is substantially non-elastic or non-compressible, and it is circulated by a pump which is coupled at its ejection side with the induction side 10 of the engine and at its induction side with the exhaust 8 of the engine. This pump, which circulates the oil, is operated by compressed air from a reservoir or holder, and the valve 15 controls the supply of air to run the pump. I have not shown the air-reservoir and pump, as these are in themselves known features.

The main purpose of the present invention is to have the piston 3 move in the cylinder for a definite distance and then stop, the movement being controlled by the valve 6. As the piston in its movement operates the controlling-valve the intermediate mechanism through which the valve is actuated is adapted to impart to the valve a greater extent of movement in proportion to the movement of the piston than is obtained by the usual mechanism employed for controlling a slide-valve. The mechanism between the piston-rod and valve-stem is such that the valve gives a full opening, has a quick movement, and is shifted back to the cut-off point by the piston when the latter shall have reached a predetermined point in the cylinder.

On the rock-shaft 23 there is a prolongation or extension 34, which is a wrist or pin for setting the engine in motion.

When the parts are disposed as seen in Fig. 1—that is, with the piston 3 at the center of its stroke and the valve 6 at the "cut-off" point, both inlet-ports being closed—the two roller-studs 26 will be disposed as seen in Figs. 3 and 4—that is, each will be entered about half its diameter into the respective slots 27 in the shorter arms of the rocker 28. Under these conditions the ends of the cylinder will be full of oil and the slide-valve 15 will be at its cut-off point. Now if we wish to set the piston 3 in motion to the right in Fig. 1 the block 19 is moved to the right a certain distance by means of the starting-wrist 34. The effect of this movement is to shift the valve

6 to the right through the medium of the arm 22 and link 21, and this movement causes the roller-stud 26 at the left in Figs. 1 and 3 to enter the slot 27 at that side, while the stud 26 at the right moves out clear of its slot. The piston now moves to the right, Fig. 1, in the cylinder and in doing so carries with it the bracket 31 and block 30, thus swinging or turning the T-shaped rocker or lever 28 about its axis at 32. The slotted arm thereon acts on the roller-stud 26, which engages the slot therein and through the floating rocker 25, shaft 23, and arm 22 shifts the valve 6 back again. When the piston shall have reached the end of its predetermined extent of movement to the right, the valve will have again returned to the cut-off point, Fig. 8, and the piston will then stop and be held or locked firmly in that position by reason of the fact that it has oil on both sides of it, and the air-valve 15 will also be at the cut-off point, both valves being coupled so as to move in unison. The position of the parts at the end of the movement of the piston to the right is shown in Fig. 8. It should be noted that the extent to which the piston will move in returning the valve to the cut-off position will be governed by the length of the levers of the intermediate mechanism between the piston-rod and the valve-stem, and it should be noted also that the leverage with which the slotted arm of the rocker 28 acts on the roller-stud of the floating rocker will be governed by the extent to which said stud is made to enter the slot by the shifting of the block 19 with the starting-wrist at starting. It should be noted also that the extent of movement of the piston will be limited and controlled by the extent to which the block 19 is moved by the starting-wrist. For example, if the block 19 should be shifted far enough (in the construction as shown) to carry the roller-stud into the slot as far as it will go the piston will be compelled to move to the end of the cylinder in order to shift the valve back to the cut-off point. By reason of the peculiar construction of the variable leverage device it follows that the longer the stroke of the piston the slower will be the return movement of the valve. As the mechanism is herein shown, if it be desired that the piston shall move from the center in the opposite direction—to the left in Fig. 1—the block 19 must be shifted to the left, so as to shift the valve 6 to the left and admit the oil to the right-hand side of the piston. When the block 19 is shifted in order to shift the valve, the shaft 23 is prevented from rocking by the engagement of the roller-stud 26 with the slot 27. The piston may, if desired, be shifted to any position in the cylinder by opening the by-pass 11 and operating the piston through mechanism comprising a rack 35 on the piston-rod, a pinion 36 gearing therewith, and a wheel 37 on the same shaft 38 with said pinion.

I do not restrict myself to the specific mech-

anism herein shown and described, as it will be obvious to any skilled mechanic that some variation in the same may be made without departing in any material degree from my 5 invention. For example, the valve 6 may be any known kind of slide-valve. I have shown the kind I prefer. The same is true of the block 30, which slides in a guideway in the pendent bracket or part 31. Obviously this 10 is a mere expedient to overcome the discrepancy between the curved path of the stud 29 and the rectilineal path of the bracket, and this may be compensated by any known device. The object in employing two slotted 15 arms on the rocking lever or rocker 28 and two arms with roller-studs on the rocker or lever 25 is to provide for the movement of the piston in both directions from its central position; but obviously the invention is fully 20 embodied in one slotted arm and one stud-carrying arm.

Having thus described my invention, I claim—

1. The combination with the engine, of mechanism between and connecting the piston-rod and valve-stem of said engine, whereby the former operates the latter, said mechanism comprising two adjacent rocking devices the arms of which have an adjustable slotted connection, and means coupling arms on the respective rocking devices with the piston-rod and valve-stem of the engine, whereby the valve of the engine may be shifted a variable distance without disturbing the said piston 35 and rod, substantially as set forth.

2. The combination with the cylinder, its piston, the piston-rod, and the controlling-valve, of mechanism between the piston-rod and valve whereby the former operates the latter, said mechanism comprising a rocking lever having a slotted arm and an arm connected by coupling means with the piston-rod, a floating rocker device having an arm pro-

vided with a stud to engage the slot in the arm of the said rocking lever and an arm connected by coupling means with the valve, and the means coupling the lever-arms to the piston-rod and valve, respectively, substantially as set forth. 45

3. The combination with the cylinder, its piston, the piston-rod, the controlling-valve, and its stem, of the mechanism between said rod and stem whereby the rod operates the valve, said mechanism comprising the T-shaped rocking lever 28, having slots 27 in 50 two of its arms, and connected to the piston-rod through its other arm, coupling means for connecting said arm with said rod, the sliding block 19, the rock-shaft 23 mounted therein, the rocking lever 25, provided with studs 26 55 to engage the respective slots in the lever 28, the arm 22 on said rock-shaft, and means coupling said arm to the valve-stem, whereby the valve may be shifted to set the piston in motion without disturbing the piston-rod, 60 substantially as set forth.

4. The combination with the engine, and mechanism between the piston-rod and valve-stem thereof, whereby the said rod in its movement actuates the valve, of a valve controlling the compressed-air supply, means connecting said valve with the valve-stem of the engine, means for opening communication between the ends of the engine-cylinder for the flow of liquid from one end to the 70 other, and means for shifting the position of the piston in the cylinder by hand, substantially as set forth. 75

In witness whereof I have hereunto signed my name this 31st day of October, 1902, in the 80 presence of two subscribing witnesses.

FRANCIS W. BRADY.
